UNITED STATES PATENT OFFICE.

CHARLES C. BLACKMORE, OF DAYTON, OHIO.

RADIO APPARATUS.

Application filed December 31, 1924. Serial No. 759,043.

My invention relates to radio apparatus and in particular to receiving apparatus.

It is the object of my invention to provide a circular or cylindrical receiving set 5 enclosed within a semi-spherical cover.

It is a further object to provide for the adjustment of certain parts of the receiving set such as the condensers by the relative movement of the semi-spherical cover 10 and the base supporting a portion of the apparatus, thus securing an adjustment and setting of the instrument without the use of the usual dials and knobs which are difficult to see, tedious to operate and confusing to a person of little scientific knowledge and experience.

It is my object to provide a set which has great simplicity, ease of adjustment, which will be self-contained and which will occupy the minimum of space.

It is a further object to provide a cover which may serve the dual purpose of a cover, and an adjusting means for the set.

It is a further object to provide such a 25 cover which will reduce outside interferences or eliminate them substantially entirely.

It is an additional object of my invention to provide means for indicating the stations which can be secured by bringing the cover 30 and base into predetermined relationship so that once an adjustment is made for tuning in predetermined stations either at the factory where the set is manufactured or by the user, the same stations can be repeatedly secured by merely turning the parts relative 35 to one another so that a pointer or the like will be placed opposite to the predetermined position of the station as indicated in plain language on the dial either by wave length, symbol for the station or the name of the 40 city in which the station is located. Thus it is possible to tune in on the station desired by placing the pointer opposite the point where such city and station is marked on the dial.

It is a further object of my invention to provide an indicating means in which said 50 designations may be readily interchanged to take care of changes in wave length, stations, etc.

It is an additional object to provide supplementary adjustments such as a vernier adjustment and a detector rheostat adjustment.

It is my object to provide simple levers for 55 controlling such adjustments.

It is a further object of my invention to provide means of carrying a looped aerial or antenna on the set in a position that is adjustable thereon and in constant communication with the set.

Referring to the drawings:

Figure 1 is a side elevation of the complete set;

Figure 2 is a section on the line 2—2 of Figure 1 showing the arrangement of the condensers and their adjustment; the rest of the apparatus carried upon the base of the instrument being omitted for the purpose of clearness in the drawing;

Figure 3 is a section on the line 3—3 of Figure 2;

Figure 4 is an elevation of one corner of the instrument showing a modified form of pointer location and scale of location;

Figure 5 indicates a section and fragmentary elevation of the preferred form of scale or indicating band having detachable strips for indicating the desired stations;

Figure 6 is a similar view showing a transparent strip carrying the designations of the stations. This strip may also be written upon if the designations are not placed behind it;

Figure 7 is a section on the line 7—7 of Figure 1;

Figure 8 is a typical diagram showing a system of wiring adapted to carry out my invention but I do not desire to be confined to any particular wiring arrangement as that has nothing to do with the essentials of my invention;

Figure 9 is a plan view of the instrument board partially broken away to show certain adjusting means below the level thereof;

Figure 10 is an elevation of the receiving set with a looped antenna mounted thereon;

Figure 11 is a section on the line 11—11 of Figure 10 looking in the direction of the arrows and showing the means for the connection and installation of the antenna shaft and communicating wires.

Referring to the drawings in detail, 1 is a semispherical cover, preferably of aluminum, adapted to rotate above a stationary base 2, which base forms the support for an instrument board. It also carries a standard 3 upon which is pivotally mounted the cover 1.

The lower margin of the cover 1 carries a series of designations applied in any desired fashion which indicate radio sending stations. This series of stations may be indicated preferably by a series of detachable paper strips 4 placed beneath a band 5 located on the lower margin of the cover 1. This band has openings 6 for writing on the strips 4. The band may be supported by a turned up U-shaped edge 7 formed on the lower rim of the cover 1.

If desired, instead of the band 5 with a series of spaced openings 6, I may use a continuous strip of paper or the like 8 behind a continuous strip of celluloid 9, or the strip 9 may be of such material that the designations may be written or printed or otherwise inscribed upon the strip.

Such methods of mounting are suggestive but it is, of course, obvious that the designations may be imprinted upon the lower margin of the cover 1 before it leaves the factory. Again, I desire to comprehend within my invention the relative movement of the base and the cover so that in some instances the base itself may be moved with the cover stationary. Again, it is possible, as I have shown in Figure 4, to mount the pointer 10 on the cover, locating the scale or indicating band or the indications in any desired fashion on the band itself, as at 11.

The set may be adjusted at the factory so that when the pointer and scale are brought to predetermined superimposed relationship the set will be in adjustment to receive from the stations so indicated on the indicating band or scale, or the owner of the set may tune in on the stations and upon doing so can then indicate the adjustment of the parts so that the same adjustment to secure the same station may be repeatedly gotten by simply bringing the scale and pointer into predetermined relationship.

Referring to Figure 3 it will be noted that the cover 1 is mounted upon a sleeve 12 and fastened thereto by a pin 13. This pin also clamps a washer 14 in position. A set screw 15 retains the several parts in locked engagement. The sleeve 12 carries integral therewith an actuating gear 16 having teeth 17 meshing with the condenser gears 18 which are mounted on condenser gear shafts respectively designated 19. These shafts are journaled in the usual end plates 20 and 21. The condenser shaft 19 carries a plurality of condenser plates 22 which rotate therewith in the usual manner while the connecting shaft 23 carries a plurality of stationary condenser plates 24. No claim is made to the particular form of condenser as this may be widely varied. The condenser is mounted upon a bracket 25 carried on the stationary post 3 on which rotates the sleeve 12. A set screw 26 carried by the sleeve 12 projects into a groove 27 in the stationary standard

3 to prevent the cover from being lifted off with the sleeve from the standard. If it is desired to remove the cover independently of the sleeve this may be effected by loosening the set screw 15.

It will be noted that from the size of the gears that there is a two to one movement so that the desired rotation of the condensers and the desired adjustment thereof as a consequence may be secured to the full extent by the rotation of the housing throughout the entire 360 degrees. It will also be understood that I desire to comprehend within my invention the use of one or a plurality of condensers or other means which may be adjusted for securing the desired stations by the relative movement of the cover and base.

The base consists of an upper instrument board 28 and a lower plate or ring 29 connected by a side wall 30 in which are the slots 31 for permitting of the movement of various handles such as the vernier condenser handle 32 and the adjusting vernier condenser generally designated 33. The handle 34 of the detector rheostat for controlling tube filament temperature also projects through a slot in the wall 30. A lever 35 is used for controlling the resistance which regulates the volume of reception.

The instrument board carries any number or combination of items used in sets which may vary from time to time. A typical installation is shown in Figures 8 and 9 where 36 indicates the tube sockets, 37 the location of audio frequency transformers, 38 tuning inductances, 39 a ground binding post, 40 an antenna binding post, 41 and 42 the terminals of the A batteries, 43 and 44 the terminals of the B batteries and 45 and 46 the terminals of the C batteries.

Referring to the supporting and mounting means for the looped aerial as shown in Figures 10 and 11, 1 is the housing or cover mounted on the collar 47 which is internally threaded at 48 to receive an externally threaded sleeve 49 which serves to clamp the cover in position. Passing through this sleeve is the shaft 50 of insulating material carrying the wires 51 and 52 of the antenna. This shaft passes downwardly through a second sleeve 53 which is threaded into the top of the insulating sleeve 54. This sleeve 53 has an overlapping head 55 overlapping the head of a sleeve 56 which is integral with both the sleeve 47 and the gear 16. The sleeve 56 is mounted on a shoulder 57 of the sleeve of insulating material 54 so that the gear and sleeve may turn on the stationary column of the insulating material 54. The shaft 50 passes within this column which is cut away at 58 and 59 to expose the contact bands 60 and 61 on the member 50. The wires 51 and 52 respectively are in electrical contact with the bands 60 and 61. These bands are in constant engagement with the

spring fingers 62 and 63 fastened on the column 54 to which are attached wires 64 and 65 by set screws 66 and 67. 68 indicates the jack for the phones or loud speaker.

It will be understood that I desire to comprehend within my invention such modifications as may be necessary to adapt it to varying conditions of use.

Having thus fully described my invention, what I claim as new and desire to secure by Letters Patent, is:—

1. In a radio receiving set, a base, a revolving cover, means on said base to support said cover, means on the supporting means for supporting a condenser, means associated with the cover to actuate said condenser carried on said supporting means, whereby as the cover is rotated the condenser is adjusted for reception of messages from various stations, and means associated with said cover and base for indicating the setting of the relative position of the cover and base and the condenser necessary for putting the set in communication with the desired station indicated, whereby as the cover is moved to a predetermined position indicated by designation of the station on the indicating means, the condenser will be so adjusted that messages will be received from that station.

2. In a radio receiving set, a base, a semi-cylindrical cover, a support for said cover, a sleeve carrying said cover and rotatably mounted on said support, a gear fixed on said sleeve, a variable condenser mounted on said support, a second gear associated with the movable elements of the condenser for adjusting it and meshing with the first mentioned gear whereby as the cover is rotated the capacity of said condenser is varied.

3. In a radio receiving set, a base, a semi-cylindrical cover, a support for said cover, a sleeve carrying said cover and rotatably mounted on said support, a gear fixed on said sleeve, a variable condenser mounted on said support, a second gear associated with the movable elements of the condenser for adjusting it, and meshing with the first mentioned gear whereby as the cover is rotated the capacity of said condenser is varied, and means carried on said set consisting of a scale and pointer whereby when the pointer is brought to a predetermined point over the scale the condenser will be adjusted to receive a message from such predetermined station.

4. In a radio receiving set, a base for supporting radio receiving apparatus such as tubes inductances, variable condensers, transformers and the like and terminals for batteries, antenna and speakers or phones, a revolving cover operatively connected with said condenser adapted by its revolution to adjust the condensers to tune in a desired station, a scale on the revolving cover indicating stations, and a pointer on the base

which when brought adjacent a predetermined station on the cover scale will indicate the adjustment of the condensers for receiving messages from that station.

5. In a radio receiving set, a base, a cover supported thereover and rotatable relatively thereto, means within said cover carried by said base adapted for the selective reception of transmitted energy, means carried by said cover to adjust said selective reception means, whereby if the cover is rotated relatively to the base the selective reception means will be positioned to receive messages from various stations, and supplementary means carried by said base for effecting a finer adjustment of the selective reception means.

6. In a radio receiving set, a base, a cover supported thereover and rotatable relatively thereto, means within said cover carried by said base adapted for the selective reception of transmitted energy, means carried by said cover to adjust said selective reception means, and indicating means to guide the operator in moving the cover so that messages may be received from the desired station.

7. In a radio receiving set, a base, a cover supported thereover and rotatable relatively thereto, means within said cover carried by said base adapted for the selective reception of transmitted energy, means carried by said cover to adjust said selective reception means, and means associated with said cover and base for indicating the setting of the relative position of the cover and base necessary for tuning in the desired station indicated whereby as the cover is moved to a predetermined position indicated by designation of the station on the indicating means, the selective reception means will be so adjusted that messages will be received from the desired station.

8. In a radio receiving set, a base, a standard carried by said base, a cover rotatably mounted on said standard, a gear carried by said cover, variable condensers supported by said standard, shafts to carry the movable members of said condensers, gears mounted on said shafts and meshing with the gear on said cover, the ratio between the gear carried by the cover and the gears associated with the condensers being two to one, whereby one revolution of the cover will effect a complete variation in the capacity of the condensers.

9. In a radio receiving set, a base, a revolving cover, means for supporting said cover, a gear associated with said cover, a plurality of condensers, gears associated with said condensers and engaging the gear of said cover whereby as the cover is rotated the condensers are simultaneously adjusted.

10. In a radio receiving set, a base, a revolving cover, means for supporting said cover, a gear associated with said cover, a

- plurality of condensers, gears for said condensers engaging the cover gear whereby as the cover is rotated the condensers are simultaneously adjusted, and means associated with the base and revolving cover for indicating stations whereby when a predetermined station is brought to a predetermined point indicating a predetermined relationship between the cover and the base
10. the condenser will be arranged for the reception of a message from the station so indicated on the indicating means at the predetermined point of relationship between the cover and the base.
15. 11. In a radio receiving set, a base, a revolving cover, means for supporting said cover, a gear associated with said cover, a plurality of adjustable condensers, gears for said condensers meshing with the cover gear whereby as the cover is rotated the condensers are simultaneously adjusted, and means associated with the base and revolving cover for indicating stations whereby when a predetermined station is brought to a predetermined point indicating a predetermined relationship between the cover and the base the condensers will be arranged for the reception of a message from the station so indicated on the indicating means at the predetermined point of relationship between the cover and the base, said base supporting a plurality of instruments for radio reception.

In testimony whereof, I affix my signature.

CHARLES C. BLACKMORE.
